DESIGN FOR AN INDIA-RUBBER SHEET

Roger Emile Casalis De Pury, London, England,
assignor to The Charnaux Patent Corset Company Limited, London, England

Application January 6, 1936, Serial No. 60,458
In Great Britain September 11, 1935

Term of patent 14 years

To all whom it may concern:

Be it known that I, Roger Emile Casalis De Pury, a subject of the King of Great Britain, residing at 33 Tregunter Road, Earls Court, London, England, have invented a new, original, and ornamental Design for India-Rubber Sheets, of which the following is a specification, reference being had to the accompanying drawing, forming part thereof.

The figure is a plan view of a portion of an India rubber sheet showing my new design.

I claim:

The ornamental design for an India-rubber sheet, as shown.

R. E. CASALIS DE PURY.
